GOLF PUTTER HEAD

Edward L. Cicero, 52-62 66th St.,
Maspeth, N.Y. 11378

Filed July 31, 1972, Ser. No. 276,652

Term of patent 14 years

Int. Cl. D21—02

U.S. Cl. D34—5 GH

FIG. 3FIG. 4*FIG. 5

FIG. 1 is a top plan view of a golf putter head showing my new design.

FIG. 2 is an alternative top plan view of my design within the inventive concept.

FIG. 3 is a view in front elevation.

FIG. 4 is a view of either side.

FIG. 5 is a bottom plan view of my golf putter head seen in FIG. 1.

I claim:

The ornamental design for a golf putter head, as shown and described.
